UNITED STATES PATENT OFFICE.

HUMPHREY D. HARROD, OF FRANKFORT, KENTUCKY.

DIRECTION-INDICATOR FOR VEHICLES.

1,277,920.

Specification of Letters Patent. Patented Sept. 3, 1918.

Application filed September 21, 1917. Serial No. 192,552.

To all whom it may concern:

Be it known that I, HUMPHREY D. HARROD, a citizen of the United States, residing at Frankfort, in the county of Franklin and State of Kentucky, have invented new and useful Improvements in Direction-Indicators for Vehicles, of which the following is a specification.

The present invention relates to signals, and aims to provide a signal primarily designed for use in connection with motor operated vehicles, for the purpose of indicating to pedestrians and the drivers of other traveling vehicles the intended course which the vehicle is about to pursue when approaching the intersection of streets, thus obviating casualties.

The principal object of the present invention is to provide a signal for the above mentioned purpose, embodying but few parts, the disposition of which is such as to produce a signal which is easy and convenient to manipulate from the driver's seat of the machine.

The nature and advantages of the invention will be better understood when the following detail description is read in connection with the accompanying drawing, the invention residing in the construction, combination and arrangement of parts as claimed.

In the drawing forming part of this specification like numerals of reference indicate similar parts in the several views, and wherein:

Figure 1 is a fragmentary side elevation of a machine showing the signal attached thereto.

Fig. 2 is a sectional view taken on line 2-2 of Fig. 1.

Fig. 3 shows several of the parts in detail.

A signal constructed in accordance with my invention preferably embodies a bracket formed from any suitable material, such as strap iron or the like, the bracket being indicated at 10 and possessing a substantially rectangular configuration. The bracket is vertically disposed beneath the hood of the car and has its uppermost branch engaged against and riveted or otherwise secured thereto as at 11. The hood of the vehicle is provided with a small opening through which is passed the reduced threaded portion of a bushing, while secured to said threaded portion of the bushing beneath the hood is a nut for holding the bushing fixed

upon the hood. The head of the bushing indicated at 12 provides a broad bearing surface which rests upon the exterior surface of the hood. The bushing is provided with a longitudinal bore opening at both ends, and positioned in this bore for rotation is a stem 14. The stem projects an appreciable distance above the hood and supports horizontally an arrow 15 through the instrumentality of which the direction of travel of the vehicle is indicated.

Horizontally disposed, and journaled between the opposed sides of the bracket is a shaft 16 provided with a worm gear 17 which meshes with a cog wheel 18 disposed at right angles to the worm and carried by the stem 14. Manifestly when the shaft 16 is rotated in one or the other direction, the indicating arrow is accordingly turned either to the right or left, while normally the arrow maintains a straightway position. Journaled upon the dash 19 is a short shaft 20 disposed in horizontal alignment with the shaft 16, the confronting extremities of these shafts being hollow to receive the adjacent extremities of a connecting rod 21. Set screws 22 or other suitable fastening means are employed to hold the connecting rod fixed relatively to the shafts 16 and 19 respectively. One end of the shaft 19 projects through the dash board, and a disk 23 which is secured to the dash in full view of the operator of the vehicle. At suitably spaced intervals on one face of the disk are arranged the letters L. S. R. indicative of the words "Left," "Straight" and "Right." Fixed upon this extremity of the shaft 19 is an arm 25 having a handle or knob 26 adapted to be grasped for the purpose of rotating the shaft 19, with a resultant turning of the indicating arrow.

Obviously the knob or handle 26 co-operates with the letters L. S. R., the latter serving as a guide for the operator in manipulating the arrow without constantly watching the latter. Normally the arrow is in a straightway position, and when it is desired to turn to the left, the knob 26 is swung in a direction to coincide with the letter L. or the word "Left" whichever may happen to be used on the disk 23. During this movement of the knob the shaft 19 is rotated with a resultant turning of the arrow to the left, thus informing pedestrians and operators of other traveling vehicles of the intent of the driver of the automobile to turn

to the left. When it is desired to turn to the right, the knob 26 is swung in a reverse direction to coincide with the letter R or the word "Right" on the disk 23, whereupon the arrow is turned to point in this direction. Under ordinary conditions, or when the vehicle is traveling forwardly, the knob 26 is positioned to coincide with the letter S., during which time the arrow is maintained in a straightway position. The signal is not only simple in construction, and consequently convenient to manipulate, but it will be noted that the mechanism of the arrow largely is concealed from view beneath the hood of the car, by reason of which fact the arrow may be painted different colors to add to the ornamental appearance of the machine.

While it is believed that from the foregoing description the nature and advantages of the invention will be readily apparent, I desire to have it understood that what is herein shown and described is merely illustrative of the preferred embodiment of the invention, and that such changes may be resorted to when desired as fall within the scope of what is claimed.

What is claimed is:—

A direction signal for motor vehicles comprising a substantially rectangular shaped

bracket, wholly disposed beneath the hood and having one of its sides engaged and secured against the hood, a bushing having a reduced threaded portion passed through the top of said hood, a nut secured to said threaded portion for holding the bushing fixed upon the hood, said bushing having a longitudinal bore opening at both ends, a vertically disposed shaft arranged within the bore and mounted for rotation, said shaft having its lower extremity journaled upon the remaining horizontally disposed portion of the bracket, with the opposite extremity projecting exteriorly of the hood, an arrow carried by the exposed extremity of the shaft, a cog carried by the shaft and arranged beneath the hood, the second horizontally disposed shaft arranged beneath the hood and having one extremity journaled between the vertically disposed parallel portion of the bracket, the opposite extremity of the shaft being journaled in the dash board of the vehicle, a worm on the second shaft meshing with the cog whereby both of said shafts are turned in unison, and means for operating the second mentioned shaft.

In testimony whereof I affix my signature.

HUMPHREY D. HARROD.
